COLLAPSIBLE SCAFFOLD AND LOCK
THEREFORHoward R. Benson and Robert H. Benson;
Knoxville, Tenn.

Application October 15, 1951, Serial No. 251,328

1 Claim. (Cl. 304—2)

1

This invention relates to collapsible scaffolds. In scaffolds of the collapsible type rigid upright end frames are provided and these frames are connected together by means of crossed bracing bars formed of either angle or tubular bars. It is an object of this invention to provide an improved releasable locking means for detachably securing the ends of the bracing bars to the end frames which will provide an improved safety factor whereby the scaffold assembly will be held against accidental collapsing after being set up.

Another object of this invention is to provide a locking means for the bracing bars of a scaffold which will gravitantly fall into locked position so that the scaffold will thereby be held against collapsing.

With the above and other objects in view, our invention consists in the arrangement, combination and details of construction disclosed in the drawings and specification, and then more particularly pointed out in the appended claim.

In the drawings,

Figure 1 is a perspective view of a collapsible scaffold having bracing bars with locking means constructed according to an embodiment of this invention, for locking the bracing bars relative to the end frames,

Figure 2 is a fragmentary vertical section on an enlarged scale, showing the locking means for the bracing bars,

Figure 3 is a fragmentary sectional view taken on the line 3—3 of Figure 2,

Figure 4 is a fragmentary sectional view taken on the line 4—4 of Figure 2,

Figure 5 is a fragmentary side elevation showing the locking means in released position.

Referring to the drawings, the numerals 10 and 11 designate generally a pair of end frames which are adapted to be disposed in upright or vertical position and are connected together by means of crossed bracing bars 12 and 14 which are pivotally connected together between the ends thereof by means of a pivot 13.

Each upright frame member 10 is formed of vertically disposed pairs of bars 15 which are connected together by upper and lower connecting bars 16 and 17 and angled bracing bars 18 are secured between the bars 16 and 17 as shown in Figure 1.

In order to provide an improved means whereby the bracing bars 12 and 14 may releasably be locked at their ends to the upright bars 15 of the vertical or end frames 10 and 11, we have provided at the end of each bracing bar, as shown more clearly in Figures 2 to 5 inclusive, a locking plate 19 which is pivotally mounted on a

2

pivot member 20 which is carried by the end of a bracing bar such as bracing bar 12.

A keeper pin 21 is secured, as indicated at 22, to the upright bar 15, projecting inwardly therefrom, and the keeper pin 21 is provided with a pair of annular keeper grooves 23 and 24. The adjacent end of bracing bar 12 is formed with an opening 25 through which the keeper pin is adapted to engage, and the locking plate 19 is also formed with a pair of oppositely extending arcuate slots 27 and 28 which extend from the opening 26 and these slots 27 and 28 are of a width such as to snugly engage the keeper pin within an annular groove or channel 23. The provision of the two keeper channels 23 and 24 provides a means whereby oppositely inclined bracing bars may be locked to a single keeper pin. In other words, where an additional end frame structure is to be used for enlarging the length of the scaffold, such additional frame or frames may be coupled to one of the two end frames 10 or 11 shown in Figure 1, by engaging the bracing bars of the additional frame structure to the keeper pins carried by the end frame members 10 and 11.

In the use of this locking structure the end frames 10 and 11 are set up in substantially upright or vertical position and the ends of the bracing bars 12 and 14 are engaged with their associated keeper pins 21. During the mounting of the bracing bars on the keeper pins the locking plate 19 will be manually held in a released position which is the position shown in Figure 5. The bracing bar is inserted on the keeper pin and moved therealong until the bracing bar contacts with the adjacent upright frame bar 15. At this time the locking plate 19 will be disposed in registry with the inner keeper groove or channel 23 and locking plate 19 may be manually swung downwardly to the position shown in Figure 2. Where the locking plate 19 is relatively loosely mounted on the pivot pin 20, the locking plate 19 will gravitantly swing downwardly to its locked position.

While the scaffold frame herein disclosed has been shown as formed out of angle iron, this frame may also be formed out of tubing, and the locking structure may be readily adapted to the tubular frame in the same manner as for the angle frame.

We do not mean to confine ourselves to the exact details of construction herein disclosed, but claim all variations falling within the purview of the appended claim.

What we claim is—

A collapsible scaffold comprising a pair of up-

right end frames, crossed pairs of bracing bars, each bracing bar having an opening adjacent each end thereof, pins fixedly carried by said end frames engageable through said openings, each pin having at least two longitudinally spaced annular grooves, and a locking plate pivotally carried by each bracing bar adjacent each end thereof, said plate having an arcuate slot having a width substantially equal to the diameter of the pin at the bottom of said grooves, said plate also having an opening intersecting said slot at the mid-point between the ends of the latter and spaced a distance from said pivot equal to the distance of said opening in said bracing bar from

said pivot, said opening having a diameter substantially equal to the diameter of said pin, rocking of said plate in either direction to dispose said slot in said groove providing for releasably locking said bracing bar to said frame in a selected one of two positions.
